UNITED STATES PATENT OFFICE

118,502

DESIGN FOR CARBON HOLDER FOR ELECTRIC ARC WELDING DEVICES

Clayton P. Nielsen, Chicago, Ill.

Application August 28, 1939, Serial No. 86,915

Term of patent 14 years

To all whom it may concern:

Be it known that I, Clayton P. Nielsen, a citizen of the United States, residing at Chicago, in the county of Cook and State of Illinois, have invented a new, original, and ornamental Design for Carbon Holder for Electric Arc Welding Devices, of which the following is a specification, reference being had to the accompanying drawing, forming a part thereof.

In the drawing:

Figure 1 is a top plan view of a carbon holder for an electric arc welding device, showing my new design;

Figure 2 is a side elevational view of the device shown in Figure 1;

Figure 3 is an end elevational view of the longer shaft of the device of Figure 1, illustrating the design of the jaw or clamp for holding the carbon; and

Figure 4 is a rear elevational view, showing the design from a position about the right-hand end as shown in Figure 1, looking toward the jaws or clamps.

I claim:

The ornamental design for carbon holder for electric arc welding devices, substantially as shown.

CLAYTON P. NIELSEN.
